BUILDING BRICK

Harold F. Zagrav, Canton, Ohio, assignor, by
mesne assignments, to Precision Building Sys-
tem, Inc., Canton, Ohio, a corporation of Ohio

Application December 15, 1947, Serial No. 791,899

3 Claims. (Cl. 72—41)

1

The invention relates to building bricks of a type designed for building a dry wall and then pouring mortar or other bonding material through internal, inter-connecting passages formed within the bricks, and the present invention is an improvement upon the pending application of John H. Stewart, Serial No. 648,638, filed February 19, 1946, now abandoned.

The object of the invention is to provide a building brick having vertical apertures therethrough and vertical and horizontal grooves adapted to register with similar grooves and apertures of similar bricks, when built into a wall, so as to provide inter-connecting passages into which mortar or other semi-liquid bonding material may be poured or forced under pressure to bond the bricks together in a solid wall.

Another object is to provide a brick of this character having horizontal, longitudinally disposed openings extending entirely therethrough and adapted to register with corresponding openings in similar bricks, when built into a wall, to provide air spaces within the wall for the purpose of heat and cold insulation.

A further object is to provide a brick of this character having a longitudinal rib on its upper side and a longitudinal recess of greater depth than the rib in its lower side for receiving the rib of a similar brick and forming a mortar passage therebetween.

A still further object is to provide a brick of this character having vertical grooves in its end faces, located between the horizontal air spaces and the adjacent side faces of the brick, and so positioned that they will communicate with the horizontal mortar spaces formed between adjacent bricks when built into a wall, whereby mortar or other semi-liquid bonding material from said horizontal mortar space will fill said vertical grooves, forming a moisture seal between the outer surfaces of the brick and the air spaces therein.

Another object of the invention is to provide such a brick in which these spaced vertical grooves in the ends of the bricks communicate through substantially horizontal grooves at their upper ends with the central vertical and horizontal grooves in the brick so as to facilitate the flow of mortar or other bonding material thereto.

The above objects together with others which will be apparent from the drawings and following description, or which may be later referred to, may be attained by constructing the improved brick in the manner hereinafter described in de-

2

tail and illustrated in the accompanying drawings, in which:

Fig. 1 is a perspective view of a building brick embodying the invention;

Fig. 2 a perspective view of a slightly modified form of the improved building brick in which the longitudinal rib at the top of the brick and the corresponding longitudinal recess at the bottom thereof are bevelled;

Fig. 3 a fragmentary, perspective view of one end of a brick such as shown in Fig. 2 provided with vertical mortar receiving grooves in its end faces located between the air spaces and the outer walls of the brick;

Fig. 4 a fragmentary perspective view of one end portion of a brick in which the vertical grooves such as shown in Fig. 3 communicate at their upper ends, through substantially horizontal grooves, with the larger, central, horizontal and vertical grooves;

Fig. 5 a fragmentary top plan view of abutting end portions of two of the improved bricks of the type shown in Fig. 4;

Fig. 6 a vertical sectional elevation through two superposed bricks of the type shown in Figs. 4 and 5;

Fig. 7 a perspective view of a quoin or corner brick;

Fig. 8 a top plan view showing the manner in which a stretcher brick abuts a quoin at a corner of a wall; and

Fig. 9 an end view of the outer end of the quoin or corner brick.

Referring first to the form of the brick shown in Fig. 1, a horizontal, longitudinally disposed rib or projection rib or projection 10 is formed upon the top of each brick, having slightly tapered side walls 11 and the substantially flat top wall 12 provided with a central, longitudinal disposed, horizontal groove 13.

A longitudinal recess 14, of slightly greater width than the rib or projection 10 and of somewhat greater depth as best shown in Fig. 6, extends horizontally along the lower side of the brick and has a centrally located, longitudinal groove 15 therein corresponding to the groove 13 in the top of the brick.

By forming the recess 14 in the bottom of the brick slightly wider than the rib 10 on the top of the brick, it will be seen that when such bricks are superposed in a wall there will be a slight lateral clearance between the tapered side walls of the recess in each brick and the tapered side walls 11 of the rib in the next lower block 55 so as to permit a slight lateral shifting of each

3

brick, if necessary, to properly align it in the wall, as it is placed in position.

Longitudinally disposed openings 16 are formed entirely through the brick, from one end thereof to the other, to form air spaces within the brick and located on opposite sides of the central vertical grooves 17 formed in the ends of the brick and communicating at their upper and lower ends with the longitudinal grooves 13 and 15.

The grooves 17 are preferably substantially half-round in cross section and adapted to form substantially round, vertical passages when the brick is butted endwise against similar bricks in a course of a wall built from such bricks.

A central, substantially round, vertical opening 18 is formed entirely through each brick, communicating at its upper and lower ends with the upper and lower longitudinal grooves 13 and 15, this central opening being of substantially the same size and shape as the vertical passages formed by the end grooves 17 when two of the bricks are butted together endwise, and is adapted to align vertically with such vertical passages, in courses above and below, when the bricks are laid up in a wall.

Since no mortar joints are visible in a wall built of these bricks, it is desirable that the abutting surfaces of the bricks fit tightly together and for this purpose the end surfaces 19, the top surfaces 20 at each side of the groove 13, of the longitudinal rib 10 and the lower surfaces 21, at each side of the longitudinal recess 14, are ground smooth flat and true, so as to provide tight joints between the bricks. In order to provide for grinding the surfaces 20, a relief groove 22 is preferably provided in the corner between each of the surfaces 20 and 11.

With the exception of the contour of the longitudinal rib at the top and the corresponding longitudinal recess at the bottom, the brick shown in Fig. 2 is otherwise the same as illustrated in Fig. 1 and above described, and for this purpose the same reference numerals are used upon all parts of this brick except said rib and the recess.

The rib 10a in this form of the brick has the bevelled top surface 12a and slightly bevelled side walls 11a and the recess 14a has the bevelled top surface 23 at each side of the central groove 15. This recess, the same as that in Fig. 1, is of slightly greater depth than the rib at the top of the brick in order to provide a longitudinal mortar receiving space therebetween when the bricks are laid up in a wall.

For the purpose of providing a moisture seal between the outer surfaces of the brick and the air spaces 16, vertical mortar receiving grooves may be formed in the end walls of the brick between the air spaces and the outer walls of the brick and extending from the sides of the rib at the top of the brick to the sides of the recess at the bottom of the brick. These grooves may be provided in either form of bricks shown in Figs. 1 and 2.

In Fig. 3 is shown the provision of such grooves upon a brick of the type shown in Fig. 2, these grooves being indicated at 24 while the remainder of the brick is of the same construction as that shown in Fig. 2 and the same reference numerals are applied to the other parts of the brick as in Fig. 2.

As shown these grooves are located between the longitudinal air openings 16 and the adjacent side walls of the brick and extend from the sides of the rib 10a to the sides of the recess 14a well as the ends 19 of the bricks, are ground

4

so that when these bricks are laid up in a wall the grooves 24 in the abutting ends of adjacent bricks in a course will form mortar receiving passages which will communicate with the longitudinal mortar receiving passages formed between the rib of each brick and the recess of the next upper brick into which the rib is received.

In Fig. 4 is shown a variation of the invention as shown in Fig. 3, and in this figure the grooves are applied to the ends of a brick of the type shown in Fig. 1. It should be understood that the grooves such as in Fig. 3 and Fig. 4 may be applied to either type of brick as shown in Fig. 1 or Fig. 2.

In this form of the brick all parts may be the same as shown in Fig. 1 with the exception of the vertical grooves 24a and the substantially horizontal grooves 25, connecting the upper ends 20 of the grooves 24a with the central, vertical grooves 17 and the central longitudinal grooves 13 of the brick. All other parts of the brick are the same as, and are indicated by the same reference numerals, as in Fig. 1.

In Fig. 5 is shown the manner in which the bricks are butted together, end to end in a course, in building a wall and in Fig. 6 is shown the manner in which one course of the bricks is placed upon another in the building of a wall. Although the particular type of brick used in each of these two views is as shown in Fig. 4, it should be understood that the various other types illustrated and above described may be fitted together in the same manner in laying up a wall.

As shown in these two views, when the bricks are laid up in a wall the adjacent ends of bricks in the same course will be butted against each other as shown in Fig. 5, the opposed vertical grooves 17 forming a substantially round vertical opening between the ends of the bricks.

In the same manner the grooves 24a of adjacent bricks will form substantially round openings extending vertically on each side of the end wall between the air spaces 16 and the adjacent outer surfaces of the brick. The horizontal grooves 25 of opposed bricks will form horizontal openings or passages extending from the central opening formed by the grooves 17 to the vertical openings formed by the grooves 24a.

As shown in Fig. 6, when one course of bricks is laid upon another, horizontal, longitudinal, disposed mortar spaces 26 will be formed between the different courses of bricks because of the ribs 10 being of less height than the recesses 14 into which they are received.

These mortar spaces are centrally enlarged by the grooves 13 and they communicate with the vertical, central openings 18 and the vertical openings formed by the grooves 17 of abutting bricks in the same course. It will also be seen in Fig. 6 that the vertical grooves 24a, located between the air spaces 16 and the adjacent outer walls of the brick, communicate at both ends with these mortar spaces 26.

Thus when mortar or other semi-liquid bonding material is poured or forced under pressure into the openings 18 and 17, it will fill the mortar spaces 26 and the vertical passages formed by the grooves 24a, not only bonding the bricks together in a solid structure but preventing moisture from passing through the joints from the outside to the air spaces 16.

Since the top and bottom edges 20 and 21, as

5

true and straight, the bricks will all fit tightly together, not only providing moisture-tight joints but presenting a pleasing appearance in the finished wall.

In Fig. 7 is shown a quoin, or corner brick, the inner end portion of which may be made in the same manner as any of the forms shown in Figs. 1 to 4 inclusive, excepting that no air spaces are provided on opposite sides of the vertical central grooves 17. This portion of the brick is shown of the type as in Fig. 1 and the same numerals are applied thereto.

The outer end portion of the quoin, or corner brick, is different each having the closed flat end 27, and a vertical groove 17' is formed in one side adapted to cooperate with an end groove 17 in the abutting stretcher brick as shown in Fig. 8. A substantially rectangular rib or projection 10' is formed upon the top of the outer end portion of the quoin, which is of the same shape as the rib 10 and provided with the longitudinal groove 13' similar to the groove 13 and having a vertical opening 18' therethrough.

It should be understood that these quoins or corner bricks are made in lefts and rights, that is the groove 17' may be formed in either side of the brick as may be required.

I claim:

1. A building brick having a longitudinal rib upon its upper side and a correspondingly shaped recess of slightly greater width and depth than the width and height, respectively of the rib, in its lower side, there being a longitudinal, centrally disposed groove in the rib and a corresponding groove in the recess, and vertical, central grooves in the ends of the brick communicating at their upper and lower ends with the ends of said longitudinal grooves, a central, vertical, opening extending entirely through the brick and communicating at opposite ends with the central portions of said longitudinal grooves, and openings extending longitudinally through the brick and spaced on opposite sides of said vertical grooves and openings, there being a longitudinal relief groove in the corner between each rib and the adjacent top surface of the brick, said top surfaces on each side of the rib and the lower surfaces on each side of the recess being ground true so that they will fit tightly against similar bricks.

2. A building brick having a longitudinal rib upon its upper side and a correspondingly shaped recess of slightly greater width and depth than the width and height, respectively of the rib, in its lower side, said rib and recess having flat upper surfaces, there being a longitudinal, centrally disposed groove in the rib, and a corresponding groove in the recess, and vertical, central grooves in the ends of the brick communicating at their upper and lower ends with the ends of said longitudinal grooves, a central, vertical,

6

opening extending entirely through the brick and communicating at opposite ends with the central portions of said longitudinal grooves, and openings extending longitudinally through the brick and spaced on opposite sides of said vertical grooves and openings, there being a longitudinal relief groove in the corner between each rib and the adjacent top surface of the brick, said top surfaces on each side of the rib and the lower surfaces on each side of the recess being ground true so that they will fit tightly against similar bricks.

3. A building brick having a longitudinal rib upon its upper side and a correspondingly shaped recess of slightly greater width and depth than the width and height, respectively of the rib, in its lower side, so that there will be a lateral clearance between the rib and recess of similar bricks, there being a longitudinal centrally disposed groove in the rib and a corresponding groove in the recess so as to provide a flat, horizontal mortar space therebetween with an enlarged central portion, a central, vertical, opening extending entirely through the brick and communicating at opposite ends with the central portions of the longitudinal grooves and, vertical, central grooves in the ends of the block communicating at their upper and lower ends with the ends of the longitudinal grooves, there being longitudinal air space openings extending entirely through the brick on opposite sides of said vertical opening and grooves, and other vertical grooves, of less width than the vertical central grooves, located in the ends of the brick between said longitudinal air space openings and the outer walls of the brick and transverse grooves in the ends of the rib communicating with said central grooves and said other vertical grooves.

HAROLD F. ZAGRAY.
